UNITED STATES PATENT OFFICE

153,374

DESIGN FOR A BOTTLE

James Miglioretti, Baltimore, Md., assignor, by mesne assignments, to Roma Wine and Liquor Company, Incorporated, Baltimore, Md., a corporation of Maryland

Application March 16, 1948, Serial No. 145,149

Term of patent 3½ years

(Cl. D58—9)

To all whom it may concern:

Be it known that I, James Miglioretti, a citizen of the United States, residing at Baltimore city, in the State of Maryland, have invented a new, original, and ornamental Design for Bottle, of which the following is a specification, reference being had to the accompanying drawing, forming part thereof.

I claim:

The ornamental design for a bottle, as shown.

JAMES MIGLIORETTI.
